UNITED STATES PATENT OFFICE.

ALEXANDER CHURCHWARD, OF NEW YORK, N. Y., ASSIGNOR TO WILSON WELDER & METALS COMPANY, INC., A CORPORATION OF NEW YORK.

ELECTRIC-ARC WELDING.

1,416,449.

Specification of Letters Patent. Patented May 16, 1922.

Application filed February 18, 1920. Serial No. 359,495.

To all whom it may concern:

Be it known that I, ALEXANDER CHURCHWARD, a citizen of the United States, residing at New York city, county of New York, 5 State of New York, have invented certain new and useful Improvements in Electric-Arc Welding, of which the following is a specification.

My invention relates to electric arc welding and particularly to a welding system of the constant-current type, where the variations in the arc current are compensated by a pressure variable carbon-pile controlled by a solenoid. One object of my invention is 10 to provide an improvement in the automatic current controlling means of such a system.

Another object is to provide means for shunting the current from the carbon-pile to a protective resistance in parallel therewith whenever the arc is short-circuited. By 20 means of this protective resistance, the overheating and burning out of the carbon-pile is positively prevented and I thereby produce a compensator which will be practically "fool-proof" and, consequently, extremely durable and having a greatly increased life.

Further objects will appear from the following description taken in connection with 30 the accompanying drawing wherein several embodiments of my invention are illustrated.

Figure 1 is a diagrammatic view of a complete welding circuit including a generator, welding electrodes, and a variable resistance 35 operated by a solenoid.

Figure 2 is a diagrammatic view of a pressure variable carbon-pile with one form of my protective resistance applied thereto.

Figure 3 is a diagrammatic view of a 40 carbon-pile similar to that in Figure 2 showing a second form of protecting resistance applied thereto.

Figure 4 is a view similar to Figures 2 and 3 but showing a third form of protective resistance.

While welding with a machine of the constant-current system above described, it is customary to operate with a comparatively low I. R. drop through the variable resistance (from 14-16 volts). When the arc is short-circuited, however, the drop through the variable resistance increases greatly, often becoming as high as 31 volts, and the current thereby produces an excessive heating effect 55 therein. Ordinarily the arc is short-circuited

only for an instant before drawing the arc and in such a short interval the variable resistance has no time to overheat. It has been found, however, that in practice, despite all precautions, the arc will often be 60 short-circuited for longer periods of time either through accident or through heedlessness in operating. Careless workers will sometimes allow the electrode to remain lying upon the work for considerable periods of 65 time, thereby causing the variable resistance to overheat and burn up rapidly.

In order to reduce the cost of renewals and avoid the danger of fire resulting from accidents or from careless operations, I have 70 conceived the idea of constructing a "fool-proof" apparatus by utilizing a safety protective resistance in shunt with the compensating resistance adapted to absorb the larger portion of the current whenever the arc is 75 short-circuited.

I have shown my protective means applied to a carbon-pile compensating resistance, and have illustrated three distinct forms thereof (see Figures 2-4). In each of the illustrated forms the carbon-pile is composed of 80 a series of resistor elements 2 arranged face to face in imperfect contact. As shown in Figure 1 the current is supplied in each instance by a motor generator 3 and may be 85 traced as follows: from the generator 3 through the wire 4, the carbon-pile 1, the wire 5, the controlling solenoid 6, the wire 7, the welding electrode 8, the work 9 and from the wire 10 back to the generator 3. 90 The compressing lever 11 is pivoted at 12 and is actuated by the difference in pull of the spring 13 and the plunger 14 operated by the controlling solenoid 6. The dash-pot 15 serves to dampen somewhat the vibrations 95 of the compressing lever 11.

The first form of my carbon-pile protective means is shown in Figure 2 and comprises the coil of resistance wire 16, preferably of "nichrome" metal, connected to each 100 one of the resistor elements 2.

In the form of pile protective means shown in Figure 3, I have shown a coil of resistance wire 16^a similar to the resistance shown in Figure 2. Instead of being connected to each of the resistor elements 2, as in Figure 2, it is connected only to the end elements and to the intermediate elements 17 and 18.

In Figure 4 I have shown a third form 110

of pile protective means comprising three parallel coils of resistance wires 19, 20 and 21 adapted to be connected by the switch 22. As will be evident, this construction allows the effective value of the protective resistance to be varied at will. This may be illustrated by an example. In one construction the coils 19, 20 and 21 were made of equal resistances, each one being capable of 10 absorbing 75 amperes. In operating this device, when the coil 19 only was employed, the protective resistance absorbed 75 amperes. When the coils 19 and 20 were both connected to the terminals of the carbon-pile 1, the protective resistance was able to carry 125 amperes. Similarly, when all three coils 19, 20 and 21 were connected in parallel to the terminals of the pile, their combined capacity was 175 amperes.

20 While I have described my invention in connection with a carbon-pile, it is obvious that the protecting resistance may be utilized on other modified forms of variable resistance compensators.

25 In each form of my invention the apparatus is so designed that the value of the variable resistance is normally much less than the value of the constant protective resistance. When the arc becomes short-circuited, however, the variable resistance will automatically increase and become greater than the protective resistance.

30 In operation, when the arc is drawn, substantially all of the current will flow through the variable resistance, but when the electrode is in contact with the plate, or the arc is otherwise short-circuited, substantially all of the current will flow through the protective resistance. Consequently, the 35 variable compensating resistance will be absolutely prevented from accidental overheating or burning out. As has been indicated above, the protective resistance renders the apparatus practically "fool-proof", and thereby I am enabled to save the cost of frequent renewals.

40 I desire it to be understood that the three embodiments herein disclosed are given only by way of illustration, and not of limitation, and that my invention may be practiced in many other ways within the scope of 45 the following claims.

I claim:

1. An electric arc welding apparatus comprising, a pressure variable compensating resistance comprising a plurality of carbon resistor elements, a bridging resistance electrically connecting two of said resistor elements, the resistance between the two carbon resistor elements being normally less than said bridging resistance.

2. In a system of electric arc welding, a welding circuit including a source of potential, a pressure variable resistance comprising a plurality of resistor elements adapted

to contact with one another, a resistance in shunt with a plurality of said elements, and means for rendering said resistance normally ineffective and for causing said resistance to absorb the larger portion of the current whenever the arc is short-circuited. 70

3. In a system of electric arc welding of the constant-current type, a welding circuit including a source of potential, welding electrodes, a pressure variable resistance responsive to the fluctuations of the arc current, a constant resistance connected in parallel with a pressure variable resistance, the latter being normally of smaller value than the constant resistance, but becoming of 80 larger value whenever the electrode and the plate are short-circuited. 75

4. An electric arc welding system comprising, a variable compensating resistance responsive to fluctuations in the current of the welding circuit, a constant resistance in parallel with the compensating resistance, the value of the constant resistance lying between the maximum and minimum values of the variable resistance. 85

5. In an electric arc welding system, a pressure variable resistance pile responsive to the fluctuations of the arc current, and an adjustable protecting resistance arranged across the terminals of the pile adapted to 95 automatically absorb substantially all of the current when the arc is short-circuited. 90

6. In a constant-current electric arc welding system a compensating resistance responsive to fluctuations in the welding current, and a protecting resistance normally substantially ineffective for absorbing substantially all of the current whenever the arc is short-circuited, whereby the compensating resistance is prevented from overheating or 105 burning out. 100

7. An arc welding apparatus comprising a compression rheostat having a pile of resistor elements arranged face to face in contact with one another and having an adjustable safety protecting resistance connected to the terminal elements of the pile said protecting resistance comprising a plurality of resistances in parallel, and means for successively connecting them. 110

8. In a constant-current electric arc welding system, a compensating resistance responsive to fluctuations in the welding current, and a protective resistance of nichrome wire bridging the terminals of said compensating resistance for absorbing the larger portion of the current whenever the arc is short-circuited, said protecting resistance comprising a plurality of parallel branches, and a switch adapted to introduce any desired number of branches into the circuit. 125

In testimony whereof, I have affixed my signature to this specification.

ALEXANDER CHURCHWARD.
